(57) **CLAIM**

The ornamental design for a medical ultrasound gel automated dispenser, as shown and described.

DESCRIPTION

FIG. 1 is a top, front and right side perspective view of a medical ultrasound gel automated dispenser showing our new design;

FIG. 2 is a bottom, front and left side perspective view thereof;

FIG. 3 is a top, rear and right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines are shown for the purpose of illustrating parts of the article that form no part of the claimed design.

1 Claim, 9 Drawing Sheets
